PIPE

Stanley Szymczak, Milwaukee, Wis.

Application April 11, 1934, Serial No. 719,984

3 Claims. (Cl. 72—52)

This invention appertains to pipes, conduits, or similar fluid conductors formed from concrete or other plastic material and generally employed in underground sewers, water-mains, culverts, and the like.

In pipes, or sewers, of this character, it is customary to build forms in the tunnel, ditch, or other excavation, and pour the concrete around the forms. Obviously, this is a laborious and expensive operation.

I am aware that it has heretofore been proposed to make the pipes, sewers, etc., from pre-cast units. In all of these units with which I am familiar, extreme difficulty is had in assembling the units, and the units cannot be associated together as the tunnel is being built.

It is, therefore, one of the primary objects of my invention to provide a pipe, or culvert, built up of pre-cast sectional units, which can be readily assembled, and which are of such a form that all sections can be brought through the built part of the pipe, or culvert, and assembled as the tunnel is being built.

Another object of my invention is to provide a pipe, or culvert, built up of pre-cast sectional units of such a construction as to permit the same to be assembled by unskilled workmen, thereby dispensing with the necessity of employing skilled artisans.

A further object of my invention is to provide a concrete or similar plastic pipe, or culvert, constructed from pre-cast sectional units with each of the units embodying three sections including an integral base section and like companion top side sections, the sections having novel interlocking means for facilitating the connection thereof, all of the sections forming a complete unit, being provided with tongues and grooves on their opposite ends for interlocking relation with the adjacent sections to form a continuous pipe, or culvert.

A still further object of my invention is to provide a novel sewer, or culvert, of the above character, which will be durable and efficient in use, one that will be simple and easy to manufacture, and one which can be placed upon the market at a reasonable cost.

With these and other objects in view, the invention consists in the novel construction, arrangement and formation of parts, as will be hereinafter more specifically described, claimed, and illustrated in the accompanying drawing, in which drawing:

Figure 1 is a transverse section through a tunnel, or sewer, showing my improved pipe, or cul-

vert, built therein, the pipe, or culvert, being shown in end elevation with parts thereof broken away and in section to illustrate structural details.

Figure 2 is a horizontal section through the pipe, or culvert, taken on the line 2—2 of Figure 1, looking in the direction of the arrows.

Figure 3 is a longitudinal section through a tunnel, or sewer, showing a part of my improved pipe, or culvert, assembled therein, the pipe, or culvert, being shown in side elevation with parts thereof broken away and in section.

Figure 4 is a view similar to Figure 3, illustrating the means of assembling the sections of the units during the building of the pipe, or culvert.

Referring to the drawing in detail wherein similar reference characters designate corresponding parts through the several views, the letter A generally indicates my improved pipe, or culvert, and B, a tunnel, or sewer, in which the conduit is placed.

My improved pipe, conduit, or culvert, comprises a plurality of like, companion units 5, and each one of the units 5 includes independent sections 6, 7, and 8. The sections 6, 7, and 8 can be formed of concrete or other plastic or ceramic material, and the sections are molded and hardened before the same are assembled to form the units 5.

The section 6 constitutes the base portion of a unit, and consequently the same is provided with side, laterally extending aprons 9 which form an enlarged base for engaging the floor of the tunnel, ditch, or other excavation. This base section 6 is formed slightly less than a half of a circle, as can be seen by referring to Figure 1 of the drawing. The upper ends of the base section 6 are formed with flat faces, or seats, 10, having projecting upwardly therefrom connecting lugs 11.

The sections 7 and 8 are of like construction, and each is slightly greater than a quarter of a circle, so that when the sections 6, 7, and 8 are assembled the same will form substantially an annular unit in end elevation.

The lower ends of the sections 7 and 8 are provided with flat seats 12 for engaging the flat seats, or faces, 10 of the base section 6, and these seats 12 are provided with sockets 13 for receiving the lugs 11.

To facilitate the interlocking of the sections 7 and 8 together, the upper meeting ends thereof are provided respectively with a socket 14 and a lug 15.

55

When these sections are assembled, a suitable cement, or the like, is placed between their meeting joints so that a substantially integral unit structure will be had.

5 All of the sections at one side thereof are provided with a forwardly extending tongue, or flange, 16. This tongue, or flange, 16 is of less diameter than the exterior diameter of the unit, and the outer face of the tongue, or flange, 16 is provided with an outstanding beveled rib 17.

10 It is to be noted that the forward faces of the sections forming the unit and the forward faces of the tongues, or flanges, 16 are inclined forwardly and toward the center of the unit.

15 The opposite faces of the sections forming the unit are provided with grooves 18 into which the ribs 17 of the flanges, or tongues, 16 are adapted to fit. It is to be noted that the portion of the sections which carry the grooves 18 have their interior diameter enlarged for the reception of 20 the tongues, or flanges, 16. Likewise, the faces 19 of these sections on opposite sides of the grooves are inclined inwardly to form intimate contact with the inclined faces of the forward ends of the sections.

25 When the sections are assembled, a suitable cement, or like material, is utilized for forming a bond between the sections.

With my improved pipe, or culvert, the sections 30 can be readily and quickly assembled to form a complete pipe without the use of skilled workmen, and the sections can be formed at a point remote from the tunnel or other excavation, if desired.

35 In Figure 4, I have illustrated one means of assembling the sections, and in this particular form as the tunnel is being dug a predetermined number of base sections 6 are placed on the floor of the tunnel and assembled, after which the two top side sections 7 and 8 of the first unit are placed 40 on the upper ends of the first base section and then swung together so as to allow the interfitting of the lug 15 in its socket 14. The other sections are now passed through the assembled unit and placed in position.

45 As the tunnel is being dug, the dirt and other débris can be wheeled away through the assembled units.

Due to the shape and size of the sections of the units, these sections can be readily passed 50 through assembled units.

55 From the foregoing description, it can be seen that I have provided an exceptionally simple and durable form of pipe, or culvert, which can be

cast exteriorly of the tunnel, or other excavation.

Changes in details may be made without departing from the spirit or the scope of my invention, but what I claim as new is:—

1. A pipe, or culvert, comprising a plurality of like companion units, each of said units including a base section and like companion top side sections, mating interlocking means carried by the meeting ends of the base section and top side sections, mating interlocking means carried by the 10 meeting ends of the top side sections, one end of the sections being provided with interior grooves extending in a transverse direction, and ribs formed on the other ends of the sections for reception in the mentioned grooves of the sections 15 of adjacent units.

2. A pipe, or culvert, comprising a plurality of interlocking like units, each of said units including a pre-cast base section and pre-cast like top side sections, lugs formed on the upper ends of 20 the base sections, sockets formed on the lower ends of the top side sections for receiving the lugs, and a lug formed on the upper end of one top side section, the upper end of the other top side section having a socket for receiving the last 25 mentioned lug, all of the sections at one end being provided with a forwardly projecting flange having an outstanding rib thereon, and all of the sections at the other end being provided with an interior reduced portion having a groove, extending in a transverse direction, as for the purpose specified.

3. A pipe, or conduit, comprising a plurality of like companion units, each of said units including a base section having an arc slightly less than 35 a semi-circle, the upper ends of the base section being provided with flat faces, and lugs formed on said flat faces, like companion top side sections, each being formed on a slightly greater arc than a quarter of a circle and having their lower ends 40 provided with flat faces and sockets for receiving the lugs on the base section, the upper ends of the top side sections being provided with flat faces having interlocking means thereon, all of said sections when assembled forming a substantially annular unit, each of the units being provided at one end with an annular flange and an outstanding rib, and all of the units at their opposite ends having their interior faces enlarged and provided with annular grooves, extending in 45 a transverse direction as for the purpose specified.

STANLEY SZYMCZAK.
